UNITED STATES PATENT OFFICE.

GEORGE McELROY, OF PLAIN CITY, UTAH.

AUTOMATICALLY-OPERATED GATE.

SPECIFICATION forming part of Letters Patent No. 730,290, dated June 9, 1903.

Application filed September 17, 1902. Serial No. 123,777. (No model.)

To all whom it may concern:

Be it known that I, GEORGE McELROY, a citizen of the United States, residing at Plain City, in the county of Weber and State of Utah, have invented certain new and useful Improvements in Automatically-Operated Gates; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to automatically-operated gates of the class which swing down to a horizontal position; and it consists in various details of construction and combinations of parts, as will be hereinafter more fully described and then specifically defined in the appended claims.

My invention is clearly illustrated in the accompanying drawings, which, with the letters of reference marked thereon, form a part of this application, and in which drawings similar letters of reference indicate like parts in the several views, in which—

Figure 1 is a perspective view of my improved gate. Fig. 2 is a view showing the gate thrown down into a horizontal position. Fig. 3 is a detail view of the tension-regulating device in connection with the spring, which is provided to assist in throwing the gate into a vertical position. Fig. 4 is a detail view of the latch mechanism. Fig. 5 is a sectional detail view of the rock-shaft and connections. Fig. 6 is a detail view in section through the shaft on which the gate is mounted and also through the trunnion on which the horizontal shaft is mounted.

Reference now being had to the details of the drawings by letter, A A designate two posts which are mounted in upright positions in the ground, and B designates a platform which has mounted upon its upper surface a series of strips C of metal which are spaced apart. The gate is made up of longitudinal metallic strips d, which are preferably of a width equal to the width of said strips C and are so placed that when the gates are turned down into a horizontal position said strips will enter the spaces between the strips C, and the

upper surfaces of said strips D, when the latter are in a horizontal position, will provide spaced bars to give a foothold for a horse and 55 form a metallic surface over which the wheels of a vehicle can pass. The ends of said strips D are fastened to the stiles D', which latter are apertured at their lower ends and are journaled on the trunnions F, said trunnions 60 being fastened to the posts, as illustrated.

Projecting from the plate F', which holds the trunnion, is a flange f, the edge of which is formed into teeth f', and F² designates a spring, one end of which engages in a hook 65 D on the outer face of the stile against the gate, and after being coiled about said trunnion its other end is bent to form a loop, serving as a handle and is adapted to be held in one or the other of said teeth f', whereby the 70 tension of said spring may be regulated.

G designates sprocket-wheels which are secured to a shaft G' in any desired manner and are provided with sockets G², adapted to receive trunnions F'. Said sprocket-wheel has 75 two lugs g integral therewith and diametrically disposed with relation to each other on one face of said sprocket-wheel to engage the opposite sides of the gate-stile for the purpose of throwing the gate down to a horizontal 80 position or raising the same to a vertical or closed position. Mounted on the inner face of each post A is a latch I. The upturned edge of said latch is inclined, as illustrated, and a pivoted dog K, which is mounted on a pivot K', carried by a bracket-arm fastened to the stile D', is adapted to ride up said incline and drop by gravity behind the vertical edge of the catch I to hold the same 85 locked. A guide K² is fastened to the stiles, 90 through which the end of the pivoted dog K is passed. N designates rods which are pivotally connected at one end to pins carried by said sprocket-wheels and at the other end to the end of said dog K.

M designates a rock-shaft which is journaled in suitable bearings at or below the surface of the ground, and said shaft has adjacent to one end a sprocket-wheel O, loosely mounted thereon and provided with a hub 100 having clutch-teeth upon opposite sides adapted to engage similar teeth carried by adjustable collars O', which co-operate with the edges of the hubs of the sprocket-wheel

to adjust the sprocket-wheel with relation to the shaft on which it is mounted to determine the proper throw thereof in each direction. A chain O^2 passes about said sprocket-wheel O , and similar short chain O^3 also passes about one of said sprocket-wheels G , which is mounted upon the shaft G' . These chains are connected together at their ends by rods O^4 , provided with turnbuckles O^5 to take up the slack of the several parts. Projecting from said shaft M are the tread-arms M' , there being two of these members fastened to each shaft M and projecting from the latter at substantially right angles to each other, one of said treads being provided for the purpose of throwing the gate down when a vehicle approaches from one direction, while the second one serves to close the gate when a vehicle comes in the opposite direction.

While I have described but one rock-shaft and its connected mechanism connected, it will be understood that both ends of the gate are equipped with similar devices for releasing the gate, and on the opposite side of the gate is a similarly-mounted rock-shaft with connections with the gate, whereby a vehicle coming from either direction may open and close the gate.

In order to limit the upward throw of the gate, bracket-arms R may be fastened to the inner face of the posts and have projecting portions, as illustrated.

From the foregoing description, in connection with the drawings, it will be observed that a gate constructed in accordance with my invention will be durable, being made of metal, may be thrown down into a horizontal position and receive the pressure of a heavily-loaded wagon by reason of the face of the gate being flush with the metallic strips on the platform and being simple in construction and substantially built will make a suitable gate for various driveways. It will also be understood that while I have described the construction illustrated I may make various alterations in the details of construction of the invention without departing from the spirit of the invention.

Having thus fully described my invention, what I claim as new, and desire to secure by Letters Patent, is—

1. An automatically-operated gate comprising posts having trunnions secured thereto, a shaft mounted on said trunnions, a gate having stiles journaled on said trunnions, a pivoted dog carried by the gate and a catch on the gate-post, a rock-shaft and means for operating the same, connections between said rock-shaft and the shaft mounted on said trunnions, whereby as the rock-shaft turns, said dog is released from the catch and the gate turned down into a horizontal position, as set forth.

2. An automatically-operated gate comprising posts, trunnions fastened thereto, a shaft journaled on said trunnions, a gate having stiles journaled on said trunnions, a dog piv-

oted to the gate, a rod connecting said dog with the shaft, a catch on the gate adapted to be engaged by said dog, a rock-shaft, tread members secured thereon, sprocket-chain, rod and wheel connections between said shafts, said shaft mounted on the trunnions adapted to rock slightly to tilt the dog before the gate is turned to a horizontal position, and means for turning the gate down to a horizontal position, as said shaft rocks, as set forth.

3. An automatically-operated gate comprising posts, trunnions carried thereby, a shaft journaled on said trunnions, a gate having stiles journaled on said trunnions, a sprocket-wheel having projections adapted to engage with the opposite faces of said stile as the shaft is rocked, a catch mounted on the post, a dog pivoted to the gate and adapted to engage said catch, a rod connecting said sprocket-wheel with the dog, a rock-shaft and tread members connected thereto and sprocket-wheel and chain connections between the same and said shaft mounted on the trunnions, as set forth.

4. An automatically-operated gate comprising the posts, trunnions secured thereto, and a shaft having one end journaled on one of said trunnions, a sprocket-wheel keyed to the other end of said shaft, and journaled on one of said trunnions, oppositely-disposed projections on the face of said sprocket-wheel, stiles journaled on the trunnions, a pivoted dog, a rod connecting the same with said sprocket-wheel, springs secured to the trunnions and engaging said stiles, a rock-shaft, tread members secured thereto, a sprocket-wheel, and chain and rod connections between said shafts, as set forth.

5. The combination with the posts, trunnions secured thereto, a shaft having socket ends journaled on said trunnions, a sprocket-wheel fastened to said shaft and having projections on one face thereof at locations diametrically opposite, a gate having stiles journaled on said trunnions, a pivoted dog mounted on the gate, rod connections between the same and said sprocket-wheel, a catch on the gate-post adapted to be engaged by said dog, a spring, one end of which is adjustably held in a toothed flange on the trunnion-carrying plate, a hook mounted on the stile in which the other end of said spring engages, a rock-shaft, a tread mounted thereon, a sprocket-wheel on said rock-shaft, and chain and rod connections between the sprocket-wheels on said shaft, as set forth.

6. In combination with the posts, the trunnions fastened thereto, the flanged plate on each trunnion having notched teeth, springs, one end of which is adjustably held in said notches, a shaft having hollow socket portions journaled on said trunnions, a sprocket-wheel mounted on said shaft and having projections on one face thereof, a gate, stiles on the gate journaled on said trunnions, and adapted to engage said projections in their movement, a catch carried by the gate-post

and a dog pivotally mounted on the gate and adapted to engage said catch; rod connections between said sprocket-wheel and dog, a platform having metallic strips, spaced apart, 5 the spaces between the strips being adapted to receive the longitudinal metallic strips of the gate as the latter is thrown into a horizontal position, a rock-shaft, treads mounted thereon, sprocket-wheels carried by said rock-shaft, and chain connections between the sprocket-wheels on said shafts, as set forth.

7. In combination with the gate-posts, the trunnions secured thereto, the gate having stiles journaled on said trunnions, springs 15 carried by the trunnions and adapted to bear against the gate, catches on the gate-post with pivoted dogs carried by the gate and adapted to engage said catches, a shaft jour-

naled on said trunnions, sprocket-wheels held to said shaft, rods connecting the same with 20 said dogs, means for turning the gate as said shaft rocks, a rock-shaft, having tread members thereon, sprocket-wheels journaled on said rock-shaft and having hub portions notched and adapted to engage clutch-collars 25 which are adjustably secured to the rock-shaft, and sprocket-chain connections between the sprocket-wheels carried by said shafts, as set forth.

In testimony whereof I affix my signature 30 in presence of two witnesses.

GEORGE McELROY.
